MULTI-STORIED BUILDING TOY

Edward F. Schrader, Compton, Calif.

Application September 7, 1956, Serial No. 608,451

1 Claim. (Cl. 46—12)

The present invention relates generally to the field of amusement devices, and more particularly to a toy that is not only interesting for a child to assemble but amusing to play with as well after it is assembled.

A major object of the present invention is to provide a toy that embodies a number of components which can be assembled to simulate the appearance of a multi-storied building, and when the components are so assembled they define a vertically extending enclosure in which an elevator may be raised and lowered to any one of the floors provided in the structure.

Another object of the invention is to provide a multi-storied structure that is particularly adapted to support a downwardly spiraling track on which a miniature or toy vehicle may be movably disposed to circle downwardly by force of gravity.

Yet another object of the invention is to supply an amusement device of relatively simple structure that can be fabricated from standard, commercially available materials, does not require elaborate plant facilities for its production, and due to the fact that it is adapted for fabrication from soft wood or other inexpensive rigid materials, can be retailed as a toy at a correspondingly low price.

A still further object of the invention is to provide a device that is not only entertaining for a child to assemble and use, but which is of educational value in that the child must carefully consider the sequence in which the components are to be assembled relative to one another in order to attain a multi-story device to which the downwardly spiraling track may be affixed.

Another object of the invention is to supply an amusement device that occupies a minimum of space prior to assembly whereby it may be retailed in a relatively small package.

These and other objects and advantages of the invention will become apparent from the following description of a preferred form thereof, and from the drawing illustrating that form, in which:

Figure 1 is a perspective view of the invention showing the multi-story portion and the elevator-defining structure thereof when assembled;

Figure 2 is a vertical cross-sectional view of the multi-story structure and elevator means taken on line 2—2 of Figure 1;

Figure 3 is a fragmentary vertical cross-sectional view of an exterior side portion of the device showing a portion of the elevator-defining means;

Figure 4 is a fragmentary top plan view of the invention taken on line 4—4 of Figure 3;

Figure 5 is a perspective view of the invention showing the downwardly spiraling ramp attached to the exterior portions thereof;

Figure 6 is a fragmentary perspective view of a portion of the ramp removably affixed to the upper deck of the structure shown in Figure 1;

Figure 7 is a vertical cross-sectional view of a transversely extending portion of the ramp;

2

Figure 8 is a perspective view of two sections of the ramp, showing the manner in which they are removably affixed to one another in abutting position; and

Figure 9 is a combined vertical cross-sectional and elevational view of the ramp showing a modified form of vehicle movably supported on the exterior rail of the ramp.

Referring to the drawing, and particularly to Figures 1 and 2 thereof for the general arrangement of the invention, it will be seen to include a base ring 10 of wood or other rigid material in which a number of circumferentially spaced downwardly extending tapered bores 12 are formed that snugly receive the lower end portions of upwardly extending supporting rods 14. A number of circular sheets of rigid material are provided, each of which serve as a floor, as can be seen in Figure 2, and for the sake of clarity herein are identified by the numerals F-2, F-3, F-4, F-5 and F-6, with each numerical suffix denoting a particular floor in the toy structure. A number of circumferentially spaced, vertically extending bores 18 are formed in sheets F-2 to F-6, which bores are in vertical alignment with bores 16 formed into ring 10. A number of tubular spacers 20 are provided that are mounted on the rods 14 to support the floors F-2 to F-6, inclusive, in the spaced relationship shown in Figure 2. Centrally disposed circular openings O-2 to O-6 are also formed in floors F-2 to F-6 respectively, and these openings have a number of circumferentially extending, vertically aligned slots 22 formed therein that extend outwardly therefrom as shown in Figure 1. Slots 22 are of rectangular cross section, and each set of vertically aligned slots (Figure 2) has a vertically extending channel-shaped guide 24 formed of a resilient solid material, such as polymerized resin or the like, that project upwardly above the upper surface of floor F-6.

Two circular rigid plates 26 and 28 are provided that are slightly larger in cross section than openings O-2 to O-6. Slots 26a and 28a, respectively, are formed in plates 26 and 28, which slots are engaged by the lower and upper end portions of guides 24. The lower portion of guides 24 (Figure 2) are slightly bowed out by plate 26, and plate 28 similarly bows the upper portions of the guides. This bowing out of the guides, due to the resiliency of the material forming same, causes the guides to grip the plates and hold them in the position shown in Figure 2, as well as maintain the guides in slots O-2 to O-6. In this manner the floor-defining means shown in Figures 1 and 2, and the elevator-defining structure also shown, are held together as an integral unit.

An elevator E is provided (Figure 2) that is vertically movable within the confines of guides 24. Elevator E includes a circular floor member 30, a circular top 32 and a number of circumferentially spaced, vertically extending members 34, preferably formed of wire, or the like, that are outwardly disposed from the bottom 30 and top 32 and slidably engage the channel-shaped guides 24. The rigid members 34 can be affixed by the use of inwardly bent end portions 34a, as shown in Figure 3, that are imbedded in the material forming the bottom 30 and top 32, or by other fastening means as preferred. The plate 28 has a circularly disposed, downwardly extending bore 36 formed therein through which a string 38 is inserted that has a pull ring 40 mounted on the free end thereof. String 38 extends downwardly to a screw 42 having an eye formed therein, which screw is rigidly affixed to the top 32 of elevator E. A number of vertically aligned slots S-2 to S-6 inclusive, are formed on the exterior portions of floors F-2 to F-6 as shown in Figure 1, and the string 38 is slidably disposed in these slots. When the string 38 is pressed into these slots, or into just one of them, the elevator is held at any desired position relative to a selected floor F-2 to F-6 (Figure 2).

The above-described form of the invention provides an interesting children's toy which is a challenge to assemble, and by manipulation of the string 38 after assembly thereof, the elevator E can be used to carry small objects such as playthings from the floor 44 to one of the desired floors F-2 to F-6, and the plaything (not shown) then rolled from the elevator onto the selected floor. For instance, a toy automobile T such as shown in phantom line in Figure 7, may be hauled from the floor 44 to one of the floors F-2 to F-6 on the elevator E and then moved therefrom onto the selected floor.

As an added feature, a spiral, downwardly extending ramp R or runway may be provided after the toy is assembled. The runway is preferably formed of curved sections of rigid material and defined by a curved base 46 that has an inwardly disposed, upwardly projecting curb 48 and an outwardly disposed rail 50. One or more transversely disposed support bars 50c are rigidly affixed to the lower surface of base 46, and the support bars are provided with a resilient clamp 52, as shown in Figure 7, that engages one of the spacers 20 or a U-shaped gripping clamp 54 formed with resilient legs as shown in Figure 6, that snap on the exterior portions of the floors F-2 to F-6 to support the ramp sections in the manner shown in Figure 5. Alternate sections of the ramp R are provided with prongs 48a and 50a that project from the ends of curb 48 and rail 50 to engage a recess 48b and a slot 50b formed in the adjoining end portions of the rail section. In other words, on one end of each ramp section prongs 48a and 50a extend from the curb 48 and rail 50, and on the opposite end recess 48b and slot 50b are formed, as shown in Figure 8. The rail 50 preferably has a longitudinally extending groove 54 formed along the upper surface thereof in which a marble 56, shown in phantom line, may be disposed at an elevated position to roll downwardly in the groove for the amusement of the child.

Each rail 50 also has a longitudinally extending groove 58 formed in the interior surface portion thereof (Figure 7). Grooves 54 and 58 serve as guides for a vertically disposed wheel 60 and a horizontally disposed wheel 62 that are rotatably supported on an inverted J-shaped hanger 64 which supports a car body 66 of any desired fanciful design on the lower extremity thereof. If desired, the car 66 may be provided with rollers 68 rotatably mounted thereon to permit the car body to be moved over floor 44. When it is desired to use the car body 66 in conjunction with the invention, the body is raised to an elevated position and the wheels 60 and 62 placed in the grooves 54 and 58, whereby the car body 66 can spiral downwardly following the configuration of the ramp due to the force of gravity.

The invention just described can be used either with or without the ramp R, but with the ramp the device provides a structural toy which has more amusement value than that of the first described structure alone.

The use and operation of the invention have been described in detail and need not be repeated herein.

The structural portion of the invention has been illus-

trated as having multi-storied floors of a circular shape, but it will be apparent that these floors can, without departing from the invention, be square, hexagonal, or other desired shape.

Although the form of the invention herein shown and described is fully capable of achieving the objects and providing the advantages hereinbefore mentioned, it is to be understood that it is merely illustrative of the presently preferred embodiment thereof and that I do not mean to limit myself to the details of construction herein shown and described other than as defined in the appended claim.

I claim:

An educational action toy adapted to develop the skill of a child in assembling a plurality of grouped elements into an integral unit, including: a base having a plurality of spaced first bores formed therein; a plurality of rods, the end portions of which are adapted to removably engage said bores to support said rods in upright position; a plurality of sheets of substantially the same overall size as said base, each of which sheets have a central opening formed therein as well as a plurality of second bores that are vertically alignable with said first bores and a plurality of circumferentially spaced slots that extend outwardly from said opening; a plurality of tubular spacers adapted to be slidably mounted on said rods and hold said sheets in spaced relationship when said second bores and rods are in engagement; a plurality of vertically positionable guides that are adapted to be removably mounted in said slots; an elevator vertically movable within the confines of said guides; means to raise and lower said elevator; a wheeled vehicle; a plurality of curved ramp segments that are adapted to be removably joined to define a downwardly spirally path; and means to removably support said segments from said spacers, which segments when so supported permit a child to raise said vehicle by said elevator to the elevation of any one of said sheets, roll said vehicle across said sheet to which it is raised, deposit said vehicle on said ramp segments and permit said vehicle to spirally travel downwardly thereon to the floor surface on which said toy is supported.
